(57) **CLAIM**

The ornamental design for a container with drain openings as shown and described.

DESCRIPTION

FIG. 1 is a perspective view of a container with drain openings showing my new design;

FIG. 2 is a side view thereof, the opposite side being a mirror image;

FIG. 3 is an end view thereof, the opposite end being a mirror image;

FIG. 4 is an alternative perspective view thereof;

FIG. 5 is a top plan view thereof;

FIG. 6 is a bottom view thereof;

FIG. 7 is an enlargement of key exemplary area 7 in FIG. 1;

FIG. 8 is an enlargement of key exemplary area 8 in FIG. 1;

FIG. 9 is an enlargement of key exemplary area 9 in FIG. 1;

FIG. 10 is an enlargement of key exemplary area 10 in FIG. 2;

FIG. 11 is an enlargement of key exemplary area 11 in FIG. 3;

FIG. 12 is an enlargement of key exemplary area 12 in FIG. 6;

FIG. 13 is an enlargement of key exemplary area 13 in FIG. 6; and,

FIG. 14 is an enlargement of key exemplary area 14 in FIG. 6.

The dashed broken lines shown in the figures represent

portions of the container with drain openings that form no part of the claimed design. The dot-dash broken lines

circumscribe enlargements of key exemplary areas and form no part of the claimed design. The dotted broken lines

represent boundaries of the claim and form no part of the

claimed design.
